LOCKING MEANS FOR ROTARY ACTUATING
BARS OF DOOR FASTENERS

George E. Dath, Mokena, Ill., assignor to W. H. Miner, Inc., Chicago, Ill., a corporation of Delaware

Application July 25, 1947, Serial No. 763,562

5 Claims. (Cl. 292—218)

1

This invention relates to improvements in door fasteners of the rotary bar actuated type for hinged doors, and more particularly to means for holding the rotary bar locked against rotation in door opening direction when the door has been forced to closed position by the fastener.

One object of the invention is to provide simple and efficient means for locking the rotary operating bar of a door fastener against rotation in door opening direction to hold the doors tightly closed, comprising a swinging operating lever connected to the bar for rotating the same, wherein the operating lever is provided with a locking extension or projection and is displaceable lengthwise of the bar to bring the locking extension thereof into position to block rotation of the bar by engagement with the outer side of the door.

Other objects of the invention will more clearly appear from the description and claims herein-after following.

In the accompanying drawings forming a part of this specification, Figure 1 is an elevational view of a portion of one of the side walls of a railway car provided with hinged doors, illustrating my improved mechanism in connection therewith. Figure 2 is a horizontal sectional view, corresponding substantially to the line 2—2 of Figure 1. Figure 3 is a view similar to Figure 1, on an enlarged scale, showing the construction at the meeting edges of the doors, the top and bottom portions of the doors being broken away. Figure 4 is a horizontal sectional view, corresponding substantially to the line 4—4 of Figure 3, illustrating the operating handle lever in full lines in a position corresponding to that shown in Figure 3, and also indicating in dotted lines the position of the same after the bar has been partly rotated by the lever. Figure 5 is a broken view, similar to Figure 4, showing the operating lever swung through an arc of 180 degrees and the right hand door swung to position at right angles to the car wall. Figure 6 is a broken view, similar to Figure 3, illustrating another embodiment of the invention. Figure 7 is a horizontal sectional view on the line 7—7 of Figure 6.

In said drawings, 10 indicates the side wall of a railway car, which is provided with the usual door opening 11, closed by a pair of hinged doors 12 and 13, swingingly supported by hinges 14—14. As is common practice, the door 12, which is that first closed, is overlapped by the door 13, and held in closed position by the latter. The door 13 carries the fastener mechanism which is of the well-known rotary bar type, comprising a vertically disposed, rotary operating bar 15, having keeper engaging crank members 16—16 at the top and bottom ends cooperating with the usual slotted keepers 17—17 for forcing

2

the door 13 open or closed. The operating bar 15 is rotatably supported by top, bottom, and intermediate bearing brackets 18, 19, and 20, fixed to the door 13, and the keepers 17 and 17 are fixed to the side wall 10 of the car above and below the door opening 11.

My improved mechanism, as shown in the embodiment of the invention illustrated in Figures 1 to 4, inclusive, comprises broadly an operating handle lever A for rotating the bar 15 of the door fastener, operatively connected to the bar for sliding movement lengthwise of the same and having a locking arm or lug thereon adapted to be positioned by displacement of said lever in vertical direction on the bar to block rotation of the latter in door opening direction.

The operating handle lever A, which is in the form of a bar, has a hand grip portion 21 at its outer end and a cylindrical sleeve-like head 22 at its inner end. The sleeve-like head 22 serves to mount the lever on the bar 15, which, as shown, is of cylindrical, transverse section and has a sliding fit within the opening of the sleeve. A pin 23 extending diametrically through the sleeve and through a lengthwise extending slot 24 in the bar serves to secure the lever A to the bar for rotating the latter. The head 22 of the lever A carries a locking finger or lug 25 at the side thereof opposite to that which carries the operating handle lever portion 21. The lug 25 is formed integral with the sleeve, that is, it is rigid with the operating handle lever. As shown in Figures 2 and 4, the finger or lug 25 is offset inwardly toward the door 13 with respect to the plane of the hand grip portion 21 of the lever so as to engage the outer surface of the door 13 and block the lever A and the bar 15 against rotation in contraclockwise direction, as viewed in Figure 2, when the parts are in the positions shown in Figures 1 and 2. To provide ample support for the operating handle lever in this last named position, the bar 15 is preferably provided with a shelf 26 in the form of a collar welded to the bar and on which the sleeve portion of the lever A is adapted to rest.

To allow the bar 15 to be rotated by the lever A to force the door 13 open or closed, the latter is provided with an outwardly opening pocket or recess 27 in the outer side thereof, which provides clearance for swinging movement of the lug 25 of the lever A when the latter is displaced upwardly on the bar to an extent to register the lug with said recess. As will be obvious, the slot 24 of the bar 15 is made of sufficient length to permit the required amount of upward sliding movement of the lever on the bar.

The operation of the improved mechanism shown in Figures 1 to 4, inclusive, is as follows: Assuming the doors to be in their closed position, with the lever A locked against rotation in door

opening direction, as shown in Figures 1 and 2, by engagement of the lug 25 of the lever with the outer side of the door 13, the attendant first slides the lever upwardly on the bar to align the same with the pocket 21, thereby unlocking the lever 5 for rotation, as shown in Figures 3 and 4. When thus unlocked, the lever is swung in contraclockwise direction, as viewed in Figure 4, to impart rotation to the bar 15 and cam the door open, the lug 27 of the lever being free to swing in the pocket or recess 21. In forcing the door 13 closed, the operation is substantially the reverse of that just described, the lever A, while horizontally aligned with the pocket or recess 21, being swung in clockwise direction to cam the door shut 15 through rotation of the bar 15, and then being dropped to the position shown in Figure 1 to lock the lever and bar against rotation in door opening direction.

Referring next to the embodiment of the invention illustrated in Figures 5 and 6, the construction is the same as that hereinbefore described with the exception that the parts are designed for a fastener which, in forcing the door open, is rotated in clockwise direction, instead of contraclockwise, as illustrated in Figures 1 to 4 inclusive. As shown in Figures 5 and 6, the operating handle lever, which is indicated by B, has a lug 125, corresponding to the lug 25 of the lever A, and is slidable vertically on the operating bar 115 to bring the lever into horizontal alignment with communicating pockets or recesses 128 and 129 in the doors 112 and 113 to provide for clearance for swinging movement of the lug 125 in the operations of forcing the door 113 open and closed. The lever B is connected to the bar to effect rotation of the latter by a pin 123 extending through a cylindrical sleeve portion 122 on the inner end of the lever B, embracing the bar 115, the pin being slidably guided in a lengthwise extending slot 124 in the bar to permit the required upward displacement of the lever in unlocking the bar for rotation. As shown in Figures 5, 6, and 7, in the locking position of the lever, the lug 125 engages the outer side of the door 112.

I claim:

1. In a door operating mechanism, the combination with a rotary operating bar mounted on the door and having keeper engaging means thereon cooperating with fixed keepers to force the door open or closed; of an operating handle lever connected to the bar for rotation therewith, said lever extending radially of said bar at one side thereof; and a locking projection on said lever projecting beyond the opposite side of said bar, said door having a recessed portion providing clearance for said projection to permit rotation of said bar in door opening direction, said lever being slidable lengthwise of said bar to a position beyond said recessed portion of the door to bring said projection in position in front of said door to block said lever against rotation in door opening direction.

2. In a door operating mechanism, the combination with a rotary operating bar mounted on the door and having keeper engaging means thereon engageable with fixed keepers to force said door open or closed; of an operating handle lever slidable lengthwise on said bar and rotatable in unison therewith, said lever having a hand grip portion extending radially of said bar at one side thereof; a locking lug on said lever projecting from the same at the opposite side of said bar

and engageable with the outer side of the door to lock said lever and bar against rotation in door opening direction; and a depression in the outer side of said door providing clearance for swinging movement of said lug to permit rotation of said bar in door opening direction when said lever is moved to a position on said bar in alignment with said depression.

3. In a door operating mechanism, the combination with a vertically disposed, rotary operating bar mounted on the door and having keeper engaging means thereon engageable with fixed keepers to force the door open or closed; of an operating handle lever comprising an arm connected at its inner end to said bar for rotation therewith and sliding movement thereon lengthwise thereof to two different positions; and a projecting lug extending from the inner end of said lever, said lug being engageable with the outer side of the door to lock said lever against rotation in door opening direction when said lever is slid to one of said positions on said bar, said door having a portion of its outer surface depressed to provide clearance for said lug of the lever during swinging movement of the same to permit rotation of said bar in door opening direction when the lever is moved to said other position on said bar.

4. In a door operating mechanism, the combination with a rotary operating bar mounted on the door and having keeper engaging means thereon engageable with fixed keepers to force the door open or closed; of an operating lever having a sleeve portion at its inner end slidable lengthwise on said bar to two different positions of adjustment, said sleeve being connected to said bar for rotation therewith; and a lug on said sleeve projecting from the side thereof opposite to said lever, said lug, in one of said positions of adjustment of said lever, being engageable with the outer side of the door to block rotation of the lever and bar in door opening direction, said door being recessed to provide clearance for said lug in the other of said positions of adjustment of said lever on said bar to permit rotation of the lever and bar in door opening direction.

5. In a door operating mechanism, the combination with a rotary operating bar mounted on the door and having keeper engaging means thereon engageable with fixed keepers to force the door open or closed, said bar having a lengthwise extending slot therein; of an operating lever including a handle portion having a guide sleeve at its inner end slidable lengthwise on said bar to two different positions of adjustment; a pin connecting said sleeve to said bar, said pin being fixed to said sleeve and extending through the slot to connect the lever to the bar for rotation in unison therewith and sliding movement lengthwise of the same; a locking projection on said sleeve; and a depression in the outer side of the door providing clearance for said locking projection to permit rotation of said lever and bar in door opening direction when the lever is in one of said positions of adjustment, said lever, when displaced to its other position of adjustment on said bar, being locked against rotation in door opening direction by engagement of the lug thereof with the outer side of the door.

GEORGE E. DATH.
